UNITED STATES PATENT OFFICE

1,965,255

AIR COOLING DEVICE

Andrew J. Peabody, Tulsa, Okla.

Application July 25, 1932, Serial No. 624,532

4 Claims. (Cl. 261—30)

My invention relates to new and useful improvements in air cooling devices in which air is injected into the device, humidified therein and then discharged therefrom into the air of a room, and has for its objects to provide an air cooling apparatus which is very light and adapted to be attached to an electric air circulating fan of the kind used in circulating air in a room; to provide such apparatus in form whereby it may be entirely mounted on and carried by said fan; to provide it in form so that it may be attached to and carried entirely by the oscillating portion of an oscillating fan and may oscillate therewith; to provide an absorbent sheet from which water may be evaporated in said device in form whereby the water thereon is readily diffused thruout the sheet; to provide a simple means whereby water may be transferred to said sheet; and to provide means of forcing or jetting the moist air upwardly from said device with an asperating effect on the air surrounding the discharge ports of the device.

With the above and other objects in view which will appear as the description proceeds, my invention consists in the novel features hereinafter set forth in detail, illustrated in the accompanying drawing and more particularly pointed out in the appended claims.

Referring to the drawing in which numerals of like character designate similar parts thruout the several views:

Fig. 1 is a view of said device in perspective, showing the intake side thereof without showing the absorbent sheet therein which carries the water to be evaporated.

Fig. 2 is a view in cross section of said device on line A—A of Fig. 3, and showing said absorbent sheet in place in said apparatus.

Fig. 3 is a view of the same in cross section on line B—B of Fig. 2, with said sheet in place in said device.

Fig. 4 is a view in side elevation of a conventional air circulating fan of the oscillating type used for circulating air in a room, and having my air cooling device attached thereto and positioned thereon, and showing said fan on a wall bracket or shelf.

Fig. 5 is a disclosure of the absorbent sheet used in said device, with A a plan view and B a longitudinal cross sectional view, of the same.

1 represents generally the shell, frame or body portion of the device, 2 a water reservoir thereon or therein, 3 a discharge port or outlet for said reservoir thru which water may escape therefrom by force of gravity to moisten or saturate an ab-

sorbent material or sheet 4 suspended or otherwise positioned in the body portion of said device by means of a rod 5 attached to said body portion 1 and by fasteners 6 near the bottom of said sheet. The sheet is held at an inclined plane 60 near its top by means of a cross bar 7 and in this position the sheet 4 may receive water as it drops from the apertures 3. Under the sheet 4 at the place where the water drops thereon is placed a strip of non-absorbent material such as 65 rubber or rubberized cloth 8 extending across the top of the sheet and by means of which the water dripping on said sheet is caused to be diffused across the entire sheet and thence downwardly over its entire surface. In the drawing this 70 non-absorbent material is shown as being folded within the hem of said sheet, which constitutes merely an inexpensive way of backing the sheet with said non-absorbent material.

A catch basin for catching any surplus water 75 from said sheet 4 is provided under said sheet by forming a closure in the bottom of the frame or body portion of the device wherein the surplus water may be caught.

The device is provided with an inlet 9 preferably round and of sufficient size to receive the desired amount of air to be humidified in the device, and an outlet 10, preferably several in number as shown in the drawing, thru which the air after it has been humidified may be forced 80 from said apparatus into the room, and which said outlets are preferably small enough to jet the air therefrom and act with an asperating effect on the air surrounding said openings. The outlets are also preferably disposed upwardly and 85 at such an angle that the air therefrom will be forced towards the ceiling of the room in several currents, it being the desire to cause the humidified air to replace the upper strata of air in the room to lower its temperature and to provide a 90 downward draft thereby. The jetting of the air upwardly also has the advantage of preventing a current of air from flowing directly from said fan.

On the device are located hooks or clamps or 100 other fastening devices 11 with which the apparatus may be attached to the fan as shown in Fig. 4 wherein is shown a fan with a conventional guard thereon and to which the apparatus is attached. This form of attachment permits the 105 apparatus to be readily placed on the fan and removed therefrom when it is not desired to use the same. The fan is shown as located on a wall bracket 13 but may rest on the floor or a table or any other customary place. The pair of lower 110

hooks 11 hook over the fan guard 14 of the fan, and for a larger fan the pair of upper hooks are used instead. Additional pairs of hooks for other sizes of fans may be provided.

5 In operation, water or other liquid is placed in the reservoir 2 and the device is hooked on the fan guard 14 of the fan 12. The device is designed so that when it is attached to the fan its bottom is positioned above the horizon of the base of the fan, so that it may clear any surface whereon the fan may rest and permits of the oscillation of the oscillating part of an oscillating fan when the device is attached to such type of fan. The device is completely carried on the 10 fan or oscillating part thereof as aforesaid. The hooks 11 are positioned on the device so that it will not only clear the base horizon as aforesaid but will position the inlet 9 in alignment with the fan so that the current of air from the fan 15 will be directed into said inlet. The apparatus is stable enough so that when the reservoir is filled with water, it will not overbalance the fan.

The water in said reservoir drips on the sheet 4 thru the apertures 3 and is diffused thruout 20 the sheet. Any surplus water is caught in the catch basin aforesaid.

Air entering the inlet 9 under draft created by the fan 12 is directed against the sheet 4 which is saturated or moistened as aforesaid, causing 25 the air to absorb said moisture from said sheet. Preferably the sheet is located within a humidifying chamber such as is shown in the drawing, said chamber being a closure except for the water inlet 3, the air outlets 10 and the air inlet 9, and in this form it not only causes the air entering the chamber to become thoroughly saturated but permits of its being forced or jetted thru an outlet or outlets 10 into the room. The 30 total cross sectional area of the outlets 10 are preferably restricted with relation to the cross sectional area of the inlet 9, to cause pressure to be built up in the humidifying chamber sufficient to cause the air to be jetted from said chamber with an asperating effect as aforesaid. It is also 35 preferred to position said outlet or outlets so that the air therefrom will be jetted upwardly as aforesaid, and when on an oscillating fan it is also advantageous to have a jet or jets so disposed on either side of a plane perpendicular to the axis of the inlet 9 and positioned substantially radially of said axis, so that with the oscillation of said apparatus the room is in effect sprayed with the humidified air therefrom.

Having thus fully disclosed my invention, what 40 I claim and desire to secure by Letters Patent is:

1. An air cooling device adapted to be mounted on an air circulating fan of the kind used for circulating air in a room, and with said device comprising a body portion, a chamber therein 45 wherein air may be humidified, a water reservoir thereon, means of transferring water from said reservoir to an absorbent material, an absorbent material as aforesaid located in said chamber and adapted for the evaporation of water therefrom and positioned to receive a current of air injected 50 into said chamber thru an air inlet thereto, a catch basin positioned below said absorbent material, an air inlet in said chamber 55 the axis of which inlet is substantially horizontally disposed, a plurality of air outlets from said chamber and with said outlets upwardly directed and substantially radially disposed with reference to said axis of said inlet, and means of mounting said device entirely on a fan as aforesaid in manner to cause a current of air from said fan to be directed into said chamber thru said inlet thereto.

80 2. An air cooling device comprising a body portion, a chamber therein wherein air may be humidified, a water reservoir thereon, means of transferring water from said reservoir to an absorbent material, an absorbent material as aforesaid located in said chamber and adapted for the evaporation of water therefrom and positioned to receive a current of air injected into said chamber, a catch basin positioned below said absorbent material, an air inlet in said chamber 85 the axis of which inlet is substantially horizontally disposed, a fan positioned at said inlet and adapted to force a draft of air into said chamber thru said inlet, means of rotating said fan, and an air outlet from said chamber the axis of which is disposed in an upward direction at an angle to the axis of said inlet.

90 3. An air cooling device adapted to be mounted on an air circulating fan of the kind used for circulating air in a room, and with said device comprising a body portion, a chamber therein wherein air may be humidified, a water reservoir thereon, means of transferring water from said reservoir to an absorbent material, an absorbent material as aforesaid located in said chamber 95 and adapted for the evaporation of water therefrom and positioned to receive a current of air injected into said chamber thru an air inlet thereto, a catch basin positioned below said absorbent material, an air inlet to said chamber the axis of which inlet is substantially horizontally disposed, an air outlet from said chamber positioned and adapted to direct air flowing therefrom upwardly and at an angle out of perpendicular, and means of mounting 100 said device entirely on a fan as aforesaid in manner such as to cause a current of air therefrom to be directed into said chamber thru said air inlet.

105 4. An air cooling device adapted to be mounted on an air circulating fan of the kind used for circulating air in a room, comprising a body portion, a water reservoir thereon, means of transferring water from said reservoir to an absorbent material, an absorbent material as aforesaid 110 located in said chamber and adapted for the evaporation of water therefrom and positioned to receive a current of air injected into said chamber thru an air inlet thereto, a catch basin positioned below said absorbent material, an air inlet to said chamber 115 the axis of which inlet is substantially horizontally disposed, an air outlet from said chamber positioned and adapted to direct air flowing therefrom upwardly and at an angle out of perpendicular, and means of mounting 120 said device entirely on a fan as aforesaid in manner such as to cause a current of air therefrom to be directed into said chamber thru said air inlet.

125 4. An air cooling device adapted to be mounted on an air circulating fan of the kind used for circulating air in a room, comprising a body portion, a water reservoir thereon, means of transferring water from said reservoir to an absorbent material, an absorbent material as aforesaid 130 located in said chamber and adapted for the evaporation of water therefrom and positioned to receive a current of air directed from a fan as aforesaid, a catch basin positioned below said absorbent material, means of mounting said device entirely on a fan as aforesaid in manner such as to cause a current of air from said fan to be directed into said air cooling device, and means in said body portion of directing said current of air therefrom upwardly after the same has been caused to absorb moisture evaporated from said absorbent material.
